[57] CLAIM

[21] Appl. No.: 175,027

The ornamental design for an inflatable, swimming cap, or similar article, as shown and described.

[22] Filed: Aug. 4, 1980

DESCRIPTION

[63] Continuation-in-part of Ser. No. 966,796, Dec. 6, 1978.

FIG. 1 is a left side perspective view of an inflatable swimming cap, or similar article showing my new design; the opposite side being a mirror image thereof;
FIG. 2 is a rear perspective view thereof;
